BRUSH

Leonard Garth Huxtable, New York, N.Y., assignor to Kellogg Brush Mfg. Co., Westfield, Mass., a corporation

Filed July 7, 1960, Ser. No. 61,267

Term of patent 7 years

(Cl. D9—2)

Fig. 1 is a front elevational view of a brush, showing my new design;

Fig. 2 is a rear elevational view thereof;

Fig. 3 is a side elevational view thereof;

Fig. 4 is a sectional view taken on line 4—4 of Fig. 2; and

Fig. 5 is a sectional view taken on line 5—5 of Fig. 2.

The dominant features of my design reside in the portions shown in full lines.

I claim:

The ornamental design for a brush, as shown and described.
